UNITED STATES PATENT OFFICE.

HARRY S. McCORMACK, OF PROVIDENCE, RHODE ISLAND, ASSIGNOR TO
UNDERWOOD TYPEWRITER COMPANY, OF NEW YORK, N. Y.; A CORPO-
RATION OF NEW JERSEY.

TYPE-WRITING MACHINE.

No. 848,678.

Specification of Letters Patent.

Patented April 2, 1907.

Application filed September 13, 1905. Serial No. 278,263.

To all whom it may concern:

Be it known that I, HARRY S. McCORMACK, a citizen of the United States, residing in Providence, in the county of Providence and State of Rhode Island, have invented 5 certain new and useful Improvements in Type-Writing Machines, of which the following is a specification.

This invention relates principally to special 10 mechanism used in type-writing machines for moving the paper in line-space direction.

In my pending application, Serial No. 245,916, filed February 16, 1905, is illustrated 15 mechanism for "condensed charging," in which a long record-sheet remains in the machine during the insertion, writing, and removal of a succession of bills or small sheets. After a written bill is removed the platen is 20 rotated backwardly, a new bill inserted, and then the platen is rotated forwardly to bring the new bill into position for writing the first line thereon.

One of the objects of the present invention 25 is to make provision for leaving either a narrow or wide space or interval between successive entries upon the record-sheet as may be desired.

A further object is to provide means for 30 enabling the platen at any time to be rotated forwardly through a mechanically-limited predetermined arc of a variable extent far beyond the capacity of the usual line-spacing mechanism; whereby the machine is adapted for addressing envelopes or for beginning the 35 writing accurately at any predetermined point far below the top edge of a sheet. This function I accomplish by the use of mechanism which is also adapted for condensed charging, so that the machine may be operated 40 for either one purpose or the other at will.

In carrying out this part of my invention 45 I provide a crank which is normally disconnected from the platen with means for connecting the platen to the crank, so that the initial rotation of the crank will cause the platen to move either backwardly or forwardly, according to the purpose for which the mechanism is being used, said means 50 preferably including reversible gearing between said crank and the platen.

Other objects and advantages will herein-after appear.

In the accompanying drawings, Figure 1 is a plan of an "Underwood" front-strike writing-machine embodying my improvements. Fig. 2 is a detail of an adjustable stop which limits the throw of the platen. Fig. 3 is an inverted plan of a latch which serves to lock the crank in connection with the platen. Fig. 4 is a sectional elevation showing part of the gearing between the crank and the platen, the parts being in normal position. Fig. 5 is a perspective view of the latch seen at Fig. 3. Fig. 6 is a fragmentary perspective view of parts seen at Fig. 4. Fig. 7 is a front elevation of the right-hand end of the platen-frame, illustrating the platen-controlling mechanism, which is shown in full lines in normal disconnected position and in dotted 70 lines as connected to the platen. Fig. 8 is an end elevation of parts seen at Fig. 7, showing the parts in normal position with the crank locked against rotation. Fig. 9 is an inverted plan illustrating particularly the means 75 for varying the space or interval between successive records upon a record-sheet. Fig. 10 is a view similar to Fig. 9, but showing the parts adjusted for different spacing between records. Fig. 11 is an elevation of parts seen 80 at Fig. 7 and also illustrating the means for reversing the connection between the crank and the platen. Figs. 12, 13, and 14 indicate different stages in the operation of the mechanism which locks the crank in connection 85 with the platen.

11 designates the usual cylindrical platen of an Underwood type-writing machine fixed upon an axle 12, journaled in a platen-frame 13, the ends of the axle projecting from the platen-frame and having finger-wheels 14 and 15 fixed thereon. The platen is also provided with the usual line-spacing devices, including a line-spacing wheel 16, rigid with the platen and advanced intermittently by a pawl 17, which is operated in the usual manner by a slide 17^a and a lever 17^b, a spring-detent 17^c being employed to retain the line-space wheel by engaging the notches thereof and being adapted to ride over the teeth 18 with which said wheel is usually provided.

Mounted upon the platen-axle 12 is a bevel-pinion 20, having the same number of teeth as the line-space wheel 16. Arranged horizontally over said pinion and normally out of

mesh therewith is a bevel-gear or curved rack 21 of greater radius than the pinion 20, so that a partial revolution of said gear may effect an entire or more than an entire revolution of said pinion and platen. Said gear 21 is fixed upon a vertical hub or shaft 22. Upon the top of the latter is fixed a crank-arm 23 by means of a screw 24, said crank having a manually-operable part or handle 25. The crank and gear are normally held up by means of a compression-spring 26, but may be pressed down at any time to bring said gear into mesh with said pinion, so that the crank may rotate the platen. Said shaft 22 is hollow and works up and down upon a fixed vertical stud 27. The latter has between its ends a head 28, perforated to fit loosely upon the platen-axle 12, and at its lower end is attached to a brace 28^a, fixed on the platen-frame. The upper end of the vertical crank-shaft 22 turns in a bearing or hole 30, formed in a fixed horizontal plate 31, which may form part of the platen-frame 13, the latter usually mounted upon a carriage 32. It will be seen that said platen-frame comprises end pieces 33 and 34, upon the latter of which said plate 31 is fastened, while a vertical plate 35, similar to the end piece 34, is fixed upon said platen-frame at the right-hand end of the platen and has a bearing 36 for the platen-axle similar to a bearing 37 in the end piece 34. It will also be noticed that the horizontal plate 31 is secured by screws 38 to flanges 39, formed upon said plates 34 and 35, thus forming a rigid structure. The spring 26 works between a shoulder 41, formed upon said stud 27, and a shoulder 42, formed within said crank-shaft 22.

Connection between the crank 23 and the platen 11 is maintained during the retraction of the platen by means of a foot 43, having the form of a lug fixed upon the upper face of the bevel-gear 21, said lug being adapted to bear against a step or ring 44, which is concentric with the axis 22 of the bevel-gear, said step being formed or provided with a cylindrical support or body 45, having a flange 46, the latter being secured by screws 47 and nuts or lugs 48 to the under side of the horizontal plate 31.

Normally the foot or lug 43 occupies a recess 49, formed in the step or ring 44, but when the crank and gear are pressed down and rotated said foot rides upon the under surface of the step 44, the platen, of course, being caused to turn or oscillate with the crank.

The return stroke of the crank is limited by a stop 50, fixed upon the plate 31; but the forward stroke of the crank (which, it will be seen, effects a backward rotation of the platen) is limited by an adjustable stop 51, carried by an arm 52, that is pivoted loosely upon the crank-shaft 22 and confined by a collar 53, fixed upon the latter. By means

of this arm the stop may be swung to any desired position concentrically with the crank-shaft 22. To hold the stop where adjusted, a circular rack or series of teeth 54 is provided concentric with said crank-shaft, the teeth formed at intervals to agree with the teeth 18 of the line-spacing wheel 16. A rotative movement of the crank 23 through an arc equal to the distance from one tooth 15 to the next will effect a rotation of the platen equal to the distance from tooth to tooth 18 of said line-space wheel. Said teeth or notches 54 are engageable by a tooth or detent 56, formed upon the end of a bar 57, pivoted at 58 to the arm 52, a spring 59 holding said detent in engagement with said rack or notches and said bar being provided with a finger-piece 60 for convenience in elevating the detent and moving it along said rack. By adjusting stop 51 in this way the stroke of the crank 23 and platen may be regulated to any desired extent between a slight platen movement and a rotation of considerably more than an entire revolution, and it will be understood that by varying the proportions of the gears it is practicable to effect a movement of the platen through even two revolutions or more, if desired, by a single vibration of the crank. In practice, however, I have found it necessary to extend the teeth 55 through more than about three-fourths of a circle, as seen at Fig. 1. The stop 51 may be set by reference to a scale 63 upon the plate 31, the stop being provided with an index 64 to coöperate with said scale, each graduation of the scale corresponding with one line-space movement of the platen.

Bearing normally against the inner side of the foot 43 is a latch 65, pivoted at 66 within the cylindrical support 45 and lying between the step 44 and the plate 31 and provided with a spring 67. The function of this latch is to vibrate outwardly over the top of the foot 43 whenever the latter moves down, thereby latching the gear down in mesh with the pinion. The normal or ineffective position of the latch is seen at Figs. 9, 10, and 13. At Fig. 14 it will be seen that the gear has been depressed, thus permitting the latch to be swung outwardly by the spring 67, as at Fig. 3. The latch now occupies a position over the foot 43 and prevents the latter from rising. Thus it will be seen that by pressing down the crank 23 the gear 21 is connected properly with the pinion 20 and locked in mesh. When the crank is swung toward the left, said foot 43 contacts with the under side of the step 44, which prevents the foot from rising. In other words, the foot bears or rides against the under side of the step 44. Upon the return stroke of the crank when the foot 43 reaches its initial rotative position (seen at Figs. 1, 13, and 14) the foot is again prevented by the latch from rising.

The backward movement of the crank, however, is continued until it reaches the fixed stop 50, so that the foot is carried back past the head 65^a of the latch, Fig. 12. Then the 5 foot trips off from the latch and is thrown upwardly by the spring 26, together with the gear and crank. The latter is at this time in contact with the stop 50, and the foot 43 occupies a notch 68, formed in the latch.

10 The dimensions of the foot and latch are such that during the backward movement past the latch the platen is rotated one or more line-spaces, and hence the forward stroke is made greater than the rearward 15 stroke thereof, so that the record-sheet is advanced automatically one or more line-spaces, insuring that the first line of the new bill shall not be written over or upon the last line of the preceding record.

20 Upon releasing the crank the latter is given a start forward by means of a spring-finger 69, which is fixed upon the crank-shaft 22 by means of a screw 70 and collar 70^a. This 25 spring rotates idly with said crank-shaft, but at the latter part of the return movement of said shaft a roll 69^a on the spring engages a sloping edge 71 and is thereby put under sufficient tension, so that when the crank is released from the control of the operator the 30 spring 69 retracts the shaft, gear, and crank until the foot or stop 43 reaches the normal rotative position. Thus the initial part of the forward movement of the crank between the stops 50 and 51 is effected without turning the platen, but the platen is rotated throughout the entire return movement of the crank, with the result already given, of feeding the record-sheet one or more extra line-spaces. At other times in the rotation 35 of the crank the flanged roll 69^a is guided by the inner edge of a fixed ring 69^b, in which is formed the sloping edge 71. During this initial movement effected by spring 69 the foot 43 engages an inclined face 65^b of the 40 latch, and carries the latter to normal position.

The record-sheet, bill, and interleaved carbon may be inserted together between the platen 11 and the usual paper shelf. They are then carried around by the usual 45 pressure-rolls (not shown) until the proper blank line upon the bill is brought to the printing-point. The bill is then written line by line, the usual line-spacing devices being employed to advance the sheets until the 50 last line is written. Thereupon the usual pressure-roller release mechanism may be operated to cast off the rollers, and the bill may then be withdrawn by pulling it up in front of the platen, while the record and carbon- 55 sheets remain in the machine undisturbed. The pressure-rolls are then permitted to return to normal position, and the operator depresses the crank 23 and pulls it forwardly as far as it will go. By this operation the 60 carbon and record sheets are rolled back for 65

a distance equal to the space occupied by the printed matter on the bill-head. Then a fresh bill is inserted and the crank is turned back as far as it will go, being arrested by the stop 50, and the spring 26 serving to dis- 70 engage the gear 21 from the pinion 20, thereby permitting free rotation of the platen in either direction. By the last movement of the crank the fresh bill is brought to the front of the platen and is then written, the carbon 75 copy thereof succeeding the copy of the first written bill upon the record sheet, a blank line appearing between the successive records. The second bill may then be withdrawn and a fresh bill inserted in the described manner 80 and the operations repeated for successive bills until the record-sheet is filled. The said recess 49 in the step or ring 44 terminates at its rear end in an abutment 75, which in co- 85 operation with a stop 76 locks the crank 23 in normal rotative position—that is, prevents undue idle rotation of the crank. The stop 76 is adjustable for the purpose of varying the extent of lost motion of the crank, and hence varying the space which is left between suc- 90 cessive entries on the record-sheet. Said stop 76 lies outside of the foot 43 and in position to be engaged by a stud 77, projecting from said foot, and is formed on the lower edge of a slide 78, which is connected by a 95 link 79 to a crank 80. The latter is fixed upon a short vertical shaft 81, mounted in the plate 31 and having on its upper end a crank or handle 82, whereby the stop 76 may be set, said handle 82 provided on its un- 100 der side with a tooth 83, adapted to spring into nicks 84, formed in a segment 85, pro- 105 vided upon said plate 31, Fig. 1, so as to de- tain the stop 78 where it is set. The segment 85 serves as a scale, the nicks being marked, 110 respectively, "1," "2," and "3" to indicate the number of spaces that will be left be- 115 tween successive entries on the record-sheet. Said stop-plate 78 has arms 86 87, which curve around the ring 45 and are held there- 120 against by a keeper 88 and work between guides 89 and 90 on one side and 91 and 92 on the other side.

When the parts are adjusted to the posi- 115 tions seen at Figs. 8 and 9, the play of the foot 43 in the recess 49 is greatest and three spaces are left between the successive records on the record-sheet. When the parts are at the Figs. 10 and 1 position, the play of the foot 49 is least and only one space is left be- 120 tween successive complete entries. When the parts are in an intermediate position, two spaces are left between successive entries. It is only necessary for the operator to adjust the hand 82 once to either "1," 125 "2," or "3" on the scale 85 in order to produce the required interval after all entries. Thus it will be seen that the adjustable stop 76 limits the idle initial movement of the manually-operable device 23 which is 130

effected by the spring 69, thereby causing variations in the advance between the forward and backward strokes of the platen effected by said member 23, so as to produce a larger or smaller interval between records.

Between the gears 21 and the platen-shaft 12 I provide a second bevel-pinion 93, and both pinions are splined at 93^a to said shaft 12. Means are provided for sliding the pinions together along the shaft, so as to bring either one or the other into position for engagement with the gear 21, Figs. 7 and 11. For effecting the shifting movement of the pinion I provide a box or U-shaped member 94, having at each end forks 95 to engage peripheral grooves 96, formed in hubs 97 98 of the pinions 20 93. The box is actuated by a lever 99, pivoted at its lower end at 100 to the strut 28^a and having a suitable connection at 101 to the shifting box and at its upper end inclined forwardly and projecting through a slot 102, formed in a yielding strip 103, the latter secured at its ends by screws 104 to the platen-frame. By means of a handle 105 upon the upper end of said lever the latter may be swung from the full-line to the dotted-line position at Fig. 11, thereby sliding the box 94, together with the pinions, along the axle 12. Formed in the lower end 30 of the slot 102 is a detent 106, which forms an obstruction to the movement of the lever between the positions Fig. 11, but yields sufficiently, owing to the springy nature of the strip 103, to permit such movement when sufficient force is supplied. The strip 103 is divided by the slot 102 into spring-jaws 107 35 108, which operate to detain the lever at the extremes of its movement, the lower jaw 108 tending to press the lever back, and this movement being opposed by the upper jaw 107, so that in forcing the lever past the obstruction 106 both jaws are slightly sprung. Thus either pinion may be mechanically maintained in engagement with 40 the gear.

At Fig. 7 the pinion 93 is shown in effective position and upon being connected to the gear 21, as seen in dotted lines, causes the initial rotation movement of the crank 23 50 to rotate the platen forwardly until the crank is arrested by the stop 51, thus bringing an envelop or sheet in the proper position upon the plate or roll to begin the first line of writing.

In order to enable the platen to be thereupon rotated line by line independently of said stop 51, I form the crank 23 in two parts, one secured by the screw 24 to the crank-shaft and the other (designated as 109) bearing the handle 25, said parts being pivoted together at 110 and the crank 23 having a guide 111 projecting up into a hole 112, formed in the part 109. A compression-spring 113 tends constantly to lift the handle 60 part 109; but it will be understood that in

pressing down the handle 25 for the purpose of connecting the gear 21 to the platen the part 109 is brought low enough, as seen in dotted lines at Fig. 7, to be arrested by the stop 51. Upon being released the part 109 is 70 pressed up by the spring 113, so that it can pass over said stop 51, and hence although the latter serves to arrest the platen, still it does not prevent succeeding line-spacing of the platen by the ordinary mechanism. The 75 platen may be fed forward line by line and the crank 23 may continue to rotate idly in the platen-advancing direction until the foot 43 is again lifted by the spring 26 into the recess 49 in the step 45, thereby disconnecting 80 the gear 21 from the platen. Thus it will be seen that in using envelops, letter-heads, or other sheets the stop 51 may be set so that when a sheet is introduced it is only necessary to depress the handle 25 and swing it as 85 far as it will go, whereupon the writing may begin, since the sheet has been brought to the exact point for beginning the first line of writing, and thereafter the writing may continue line by line independently of the 90 mechanism seen at the right of Fig. 1. The stop 50 is provided with a sloping back, as at 114, Fig. 7, to permit the member 109 of the crank to ride freely over the same after it has passed the stop 51.

Variations may be resorted to within the scope of my invention and portions of my improvements may be used without others.

The invention is applicable to paper-rollers or pressure-rollers, as well as to platens in some cases.

Having thus described my invention, I claim—

1. In a type-writing machine, the combination with a revolute platen, of a rotatable 105 finger-piece, and reversing-gear connecting said finger-piece to the platen.

2. In a type-writing machine, the combination with a revolute platen having an axle, of a gear, and a pair of pinions splined 110 to said axle one upon each side of said gear, and engageable with the latter singly.

3. In a type-writing machine, the combination with a revolute platen having an axle, of a gear, a pair of pinions splined to 115 said axle one upon each side of said gear, and engageable with the latter singly, and a finger-piece connected to said pinions for moving them to and fro upon the platen-axle.

4. In a type-writing machine, the combination with a revolute platen of a gear, a pair of pinions connected to the platen to rotate therewith, one pinion upon each side of said gear, and means for mechanically maintaining engagement of said gear with either 125 of said pinions.

5. In a type-writing machine, the combination with a revolute platen, having an axle, of a gear, a pair of pinions upon opposite sides of said gear, said pinions splined to said 130

axle, a lever controlling said pinions, and means for mechanically maintaining either of said pinions in engagement with said gear.

6. In a type-writing machine, the combination with a revoluble platen having an axle, of a gear, a pair of pinions upon opposite sides of said gear, said pinions splined to said axle, a sliding box connected to said pinions, a shifting-lever connected to said box, and a pair of spring-jaws between which said lever projects, said jaws provided with means for detaining said lever at the extremes of its box-shifting movement.

7. In a type-writing machine, the combination with a revoluble platen and a line-spacing mechanism, of a rotatable actuator normally disconnected from the platen, means for effecting connection between the actuator and the platen so that said actuator may advance the latter, a stop for arresting such advance movement of platen and actuator, whereby successive sheets may be inserted and carried around the platen and each brought to the same point for beginning the first line of writing, means permitting immediate release of the platen and actuator from said stop without retracting the platen, whereby the platen may be advanced line by line immediately after its arrest by said stop and independently thereof, and means for mechanically disconnecting said actuator from said platen upon its return to normal rotative position.

8. In a type-writing machine, the combination with a revoluble platen and a line-spacing mechanism, of a finger-piece normally disconnected from the platen, means between the finger-piece and the platen for enabling the former to rotate the latter through about an entire revolution, and an adjustable stop for limiting the advance rotation of the platen by said finger-piece; means being provided to cause the release of said finger-piece to effect dissociation of said stop with the platen immediately upon the arrest of the latter by said stop, whereby after being advanced by said finger-piece to the proper point to begin the first line of writing, the platen may be immediately advanced line by line past said stop.

9. In a type-writing machine, the combination with a revoluble platen and a line-spacing mechanism, of a revoluble finger-piece normally disconnected from the platen, means for effecting operative connection between the finger-piece and platen and for mechanically maintaining such connection, so that the finger-piece may advance the platen at a single stroke through a large number of ordinary line-spaces, a stop for arresting the advance movement of the platen effected by said finger-piece, and means for mechanically dissociating said stop from said platen upon the arrest of the platen by said stop, so that

the platen may be advanced line by line past said stop.

10. In a type-writing machine, the combination with a revoluble platen and a line-spacing mechanism, of a crank normally disconnected from the platen, means for enabling the crank by a single stroke from its normal rotative position to effect about a complete advance revolution of said platen, an adjustable stop for arresting the platen and crank, and means for enabling the platen to be immediately advanced from its position of arrest past said stop.

11. In a type-writing machine, the combination with a revoluble platen and a line-spacing mechanism, of a revoluble finger-piece normally disconnected from the platen, means for effecting operative connection between the finger-piece and platen and for mechanically maintaining such connection, an adjustable stop for arresting the advance movement of the platen effected by said finger-piece, and means for enabling said finger-piece while still mechanically connected to the platen, to pass by said stop.

12. In a type-writing machine, the combination with a revoluble platen and a line-spacing mechanism, of a revoluble finger-piece normally disconnected from the platen, means for effecting operative connection between the finger-piece and platen and for mechanically maintaining such connection, an adjustable stop for arresting the advance movement of the platen effected by said finger-piece, means for enabling said finger-piece while still mechanically connected to the platen, to pass by said stop; and means operating at the completion of the revolution of said finger-piece for effecting its disconnection from the platen.

13. In a type-writing machine, the combination with a revoluble platen and a line-spacing mechanism, of a crank normally disconnected from the platen, means for effecting operative connection between the crank and the platen so that by a single stroke of the crank the platen may be rotated through at least the major portion of an entire revolution, adjustable means for determining the length of stroke of the crank, and means for releasing the platen and the crank from said stroke-determining means while the platen and crank remain operatively connected.

14. In a type-writing machine, the combination with a revoluble platen and a line-spacing mechanism, of a revoluble finger-piece normally disconnected from the platen, means for effecting operative connection between the finger-piece and the platen, a rack curved concentrically with the axis of motion of said finger-piece, a stop adjustable along said rack, for arresting the platen-rotating movement of said finger-piece, and means operating upon the release of said

- finger-piece for releasing the same from said stop to permit the finger-piece and platen to advance past said stop.
15. In a type-writing machine, the combination with a revoluble platen and a line-spacing mechanism, of a rotatable finger-piece normally disconnected from the platen, means for connecting said finger-piece to the platen and mechanically maintaining such connection, a stop, a normally ineffective abutment connected to said finger-piece and depressible thereby so as to engage said stop when the finger-piece is rotated, and a spring for lifting said abutment clear of the stop.
- 15 16. In a type-writing machine, the combination with a revoluble platen and a line-spacing mechanism, of a crank, movement-multiplying gearing between the crank and the platen, said crank and platen being normally disconnected, means for enabling the crank to become connected with the platen so that the movement of the crank from normal position gives the platen an advance rotative movement, a stop for limiting the advance rotation of the platen effected by said crank, and means for enabling the platen to be thereupon immediately advanced by said line-spacing mechanism past said stop.
17. In a type-writing machine, the combination with a revoluble platen and a line-spacing mechanism, of a crank, a pinion connected to the platen, a gear connected to the crank but normally disconnected from said pinion, means for enabling said gear to be moved into mesh with said pinion, means for mechanically maintaining such connection, a stop for arresting the platen-advancing movement of said crank, and means releasing the crank from said stop while said gear and pinion remain in mesh.
18. In a type-writing machine, the combination with a revoluble platen and a line-spacing mechanism, of a crank, a pinion connected to the platen, a gear connected to the crank, but normally disconnected from said pinion, means for enabling said gear to be moved into mesh with said pinion, means for mechanically maintaining such connection, a stop for arresting the platen-advancing movement of said crank, means releasing the crank from said stop while said gears remain connected, and means disconnecting said gears upon the movement of said crank to normal rotative position.
- 55 19. In a type-writing machine, the combination with a revoluble platen and a line-spacing mechanism capable of rotating the platen at each stroke through several line-spaces, of a mechanism normally disconnected from the platen and capable by its initial movement from normal position of advancing the platen at a single stroke through a much larger number of line-spaces, and an adjustable stop for limiting the movement of the last-mentioned line-spacing mechan-
- ism; means being provided for mechanically dissociating said platen from said stop immediately upon completion of said initial movement, so that the platen may be advanced from its position of arrest past said stop by the first-mentioned line-spacing mechanism.
20. In a type-writing machine, the combination with a revoluble platen and a line-spacing mechanism, of a crank normally disconnected from the platen, means for enabling a movement of said crank to effect connection between the crank and the platen so that the initial movement of the crank advances the platen, a stop for arresting the platen-advancing movement of said crank, and a spring which immediately releases the platen from said stop upon the release of the crank at the completion of such initial movement of the crank.
21. In a type-writing machine, the combination with a revoluble platen, of a rotatable finger-piece normally disconnected from the platen, means for effecting and maintaining such mechanical connection between the finger-piece and the platen that the initial movement of the finger-piece may advance the platen, a stop for arresting the platen-advancing movement of said finger-piece, and means for releasing the finger-piece from said stop while the finger-piece and platen are still connected, and means for subsequently disconnecting the finger-piece from said platen.
22. In a type-writing machine, the combination with a revoluble platen, of a rotatable finger-piece normally disconnected from the platen, means normally locking said finger-piece against rotation, means for effecting and maintaining such mechanical connection between the finger-piece and the platen that the initial rotative movement of the finger-piece may advance the platen, a stop for arresting the platen-advancing movement of said finger-piece, means for releasing the finger-piece from said stop, while the finger-piece and the platen are still connected, and means for subsequently disconnecting the finger-piece from the platen, and restoring the finger-piece to normal locked condition when it reaches its initial rotative position.
23. In a type-writing machine, the combination with a revoluble platen, of a finger-piece normally disconnected from the platen, means for effecting and maintaining connection between the finger-piece and platen, said connecting means including a reversing-gear whereby the initial movement of the finger-piece may be caused either to advance or retract the platen at will, and stops for arresting the forward and backward movements of the platen effected by said finger-piece.
24. In a type-writing machine, the combination with a revoluble platen, of a rotatable finger-piece, reversing-gearing connecting said finger-piece to the platen, and relatively

adjustable stops for arresting the forward and backward movements of the platen effected by said finger-piece.

25. In a type-writing machine, the combination with a revoluble platen, of a finger-piece normally disconnected from the platen, means locking said finger-piece in normal position, means for effecting and maintaining connection between said finger-piece and the platen, said connecting means including reversing-gearing, and relatively adjustable stops for limiting the forward and backward movements of the platen effected by said finger-piece.

15 26. In a type-writing machine, the combination with a revoluble platen, of a finger-piece normally disconnected from the platen, means locking said finger-piece in normal position, means for effecting and maintaining connection between said finger-piece and the platen, said connecting means including reversible gearing, relatively adjustable stops for limiting the forward and backward movements of the platen effected by said finger-piece, means for enabling said finger-piece to pass said stops, and means for disconnecting the finger-piece from the platen.

27. In a type-writing machine, the combination with a revoluble platen, of a finger-piece normally disconnected from the platen, means locking said finger-piece in normal position, means for effecting and maintaining connection between said finger-piece and the platen, said connecting means including reversible gearing, relatively adjustable stops for limiting the forward and backward movements of the platen effected by said finger-piece, means for enabling said finger-piece to pass said stops, and means for disconnecting 40 the finger-piece from the platen and restoring it to its normal locked condition.

28. In a type-writing machine, the combination with a revoluble platen having an axle, of a gear, a pair of pinions splined to said axle one upon each side of said gear, and engageable with the latter singly, said gear normally disconnected from said pinions, a finger-piece for operating said gear, means for effecting and maintaining connection between said gear and either of said pinions, and relatively adjustable stops for variably limiting the forward and backward movements of said finger-piece, gear and platen.

29. In a type-writing machine, the combination with a revoluble platen having an axle, of a gear, a pair of pinions splined to said axle one upon each side of said gear and engageable with the latter singly, said gear normally disconnected from said pinions, a finger-piece for operating said gear, means for effecting and maintaining connection between said gear and either of said pinions, relatively adjustable stops for limiting the forward and backward movements of said finger-piece, gear and platen, and means for

enabling the platen to be rotated independently of said stops.

30. In a type-writing machine, the combination with a revoluble platen, of a rotatable actuator normally disconnected from the platen, reversing-gear for connecting the actuator to the platen so that the latter may be either advanced or retracted at the initial movement of the actuator from normal position, adjustable stops for limiting the initial movement of the actuator, means permitting release of the platen and actuator from said stop so that the advance movement of the platen may continue, a stop for limiting the return movement of the actuator to normal rotative position, and means for mechanically disconnecting said actuator from said platen upon the return of the actuator to normal rotative position.

31. In a type-writing machine, the combination with a revoluble platen, of a rotatable finger-piece normally disconnected from the platen, means locking said finger-piece in normal rotative position, reversing-gear for effecting operative connection between the finger-piece and platen so that the latter may be either advanced or retracted at the initial rotation of said finger-piece, means for mechanically maintaining such connection, a stop for limiting the initial rotation of the finger-piece and platen, means for mechanically dissociating said stop from said platen so that the latter may be advanced line by line independently of said stop, a stop for limiting the return movement of the finger-piece, and means for disconnecting the finger-piece from the platen upon the return of the former to normal rotative position.

32. In a type-writing machine, the combination with a revoluble platen, of a revoluble finger-piece normally disconnected from the platen, reversing-gear for effecting connection between the finger-piece and platen so that the latter may be either advanced or retracted by the initial movement of the former, relatively adjustable stops for limiting the back-and-forth movement of said finger-piece, and means for enabling the finger-piece to pass said stops.

33. In a type-writing machine, the combination with a revoluble platen, of a revoluble finger-piece normally disconnected from the platen, means for effecting connection between the finger-piece and platen so that the latter may be either advanced or retracted by the initial movement of the former, relatively adjustable stops for limiting the back-and-forth movement of said finger-piece, means for enabling the finger-piece to pass said stops, means for disconnecting the finger-piece from the platen when the former reaches normal rotative position, and means for locking said finger-piece in normal rotative position.

34. In a type-writing machine, the combi-

- nation with a revolute platen, of a crank, a pair of pinions connected to the platen, a gear connected to the crank but normally disconnected from the pinions, means for enabling said gear to move into mesh with either pinion for effecting either advance or retraction of the platen at the initial movement of the gear, means for maintaining such connection, relatively adjustable stops for arresting the forward and backward movements of said crank, means for enabling the crank to pass said stops, and means disconnecting the gear from the pinion upon the return of the gear to normal rotative position.
35. In a type-writing machine, the combination of a platen, a normally disconnected manually-operable device for rotating the platen, means for connecting said manually-operable device to the platen, stops for limiting the forward and backward strokes of said manually-operable device, and adjustable means for causing the backward strokes to be variably shorter than the forward strokes of the platen that are effected by the reciprocation of said manually-operable device between said stops.
36. In a type-writing machine, the combination of a revolute platen, relatively adjustable stops for arresting both forward and backward revolutions of the platen, and mechanism controlling the strokes of the platen in such a manner as to cause one stroke of the platen to be longer than the other stroke between said stops; said stroke controlling mechanism including a part adjustable for causing variations in the difference between the forward and backward strokes of the platen.
37. In a type-writing machine, the combination with a revolute platen, of a manually-operable device for rotating the platen, stops for limiting the forward and backward strokes of the platen, and adjustable means for causing varying initial portions of the platen-retracting strokes of said manually-operable device to be ineffective.
38. In a type-writing machine, the combination with a platen, of a normally disconnected manually-operable device for rotating the platen backward and forward, stops limiting the strokes of said manually-operable device, means for connecting said manually-operable device to the platen and disconnecting it therefrom, means for mechanically effecting an idle initial movement of said manually-operable device and an adjustable stop for limiting such initial movement.
39. In a type-writing machine, the combination with a platen, of a normally disconnected manually-operable device for rotating the platen backward and forward, stops limiting the strokes of said manually-operable device, means for connecting said manually-operable device to the platen and disconnecting it therefrom, means for mechanically effecting an idle initial movement of said manually-operable device, an adjustable stop for variably limiting such initial movement, and a finger-piece connected to said adjustable stop for setting the same.
40. In a type-writing machine, the combination with a platen and a manually-operable rotative device normally disconnected from the platen, of means for enabling an axial movement of said rotative device to connect the latter to the platen, a foot upon said rotative device, a latch engaging said foot to lock said device in connection with the platen, a step for maintaining such connection during the rotation of the platen forwardly and backwardly by said rotative device; said stop having a recess normally occupied by said foot, a spring for effecting the return axial movement of said rotative device, a spring for turning said rotative device idly in the platen-retracting direction while disconnected from the platen, and an adjustable stop for variably limiting such idle movement.
41. In a type-writing machine, the combination with a revolute platen, of a pinion connected to the platen, a gear normally disengaged from said pinion, means for effecting engagement between said gear and said pinion at will, relatively adjustable stops for limiting the movement of said gear and platen forwardly and backwardly, means for mechanically maintaining said gear in mesh for a greater platen-advancing than platen-retracting movement, and adjustable means for varying the difference between the platen-advancing and platen-retracting movements.
